[54] BICYCLE SAFETY FLAG

[57] CLAIM

[76] Inventor: Donald Huntington, 1471 Home Ave., Menasha, Wis. 54952

The ornamental design for a bicycle safety flag, as shown and described.

[**] Term: 14 Years

DESCRIPTION

[21] Appl. No.: 25,849

FIG. 1 is a perspective view of a bicycle safety flag showing my new design, the opposite side of the pennant being a mirror image of the side shown.

[22] Filed: Apr. 2, 1979

FIG. 2 is a fragmentary perspective view taken from the side and rear on an enlarged scale.

[51] Int. Cl. .... D10—06

FIG. 3 is a fragmentary top plan view thereof on an enlarged scale.

[52] U.S. Cl. D10/109

FIG. 4 is a fragmentary front elevational view thereof on an enlarged scale.

[58] Field of Search .... D10/109; 116/28 R, 173, 116/174, 175; 340/134; 248/534, 538, 540, 541; 280/289

FIG. 5 is a fragmentary rear elevational view on an enlarged scale.

U.S. PATENT DOCUMENTS

D. 233,510 11/1974 Baker D10/109
D. 239,926 5/1976 Baker D10/109

FIG. 6 is a fragmentary bottom plan view thereof on an enlarged scale.

FIG. 7 is a fragmentary right side view thereof on an enlarged scale.

FIG. 8 is a fragmentary left side view thereof on an enlarged scale.

The safety flag is fragmentarily shown in FIGS. 1-8 for convenience of illustration, it being understood that the staff and pennant would normally appear in the side, top, bottom, front and rear views.
